UNITED STATES PATENT OFFICE.

ADOLPH MARCUS, OF LOUISVILLE, KENTUCKY.

REINFORCEMENT FOR BASKETS.

1,071,766.

Specification of Letters Patent.

Patented Sept. 2, 1913.

Application filed August 24, 1912. Serial No. 716,801.

To all whom it may concern:

Be it known that I, ADOLPH MARCUS, a citizen of the United States, residing at the city of Louisville, in the county of Jefferson 5 and State of Kentucky, have invented certain new and useful Improvements in Reinforcement for Baskets, of which the following is a specification.

This invention relates to means for preventing the breaking of the handles and bottoms of market-baskets.

The style of market-basket generally known as a "split-basket" is in extensive use despite its fragility, on account of 15 its lightness and low cost. Retail dealers make extensive use of them for delivery purposes, as their customers frequently desire that the basket be left, with the order, and they can not well decline to accede to 20 the request. And as the baskets are seldom returned they cannot afford to use an expensive basket. But losses sustained by damage to orders in course of delivery, due to breaking of handles, separation thereof 25 from the body of the basket or the breaking-out of the bottom, increases the cost of delivery by such baskets to a point that is a matter of some moment.

An object of this invention is to provide 30 a reinforcement that will render this class of baskets trustworthy in delivery service, preventing losses due to their breakage, and that may be readily removed when it is desired to leave the basket with a customer, 35 and that may be readily applied to another basket.

A further object is to provide a reinforcement that may be so cheaply constructed as to permit of its universal use.

With the foregoing objects in view the 40 invention consists of the novel construction hereinafter set forth, and illustrated in the accompanying drawing, that forms a part of this specification, in which—

Figure 1, is a side elevation and Fig. 2, 45 an end elevation of a basket with my invention applied; Fig. 3 being a perspective of the band.

Referring to the drawing in which like 50 reference numerals indicate like parts in the different views; 1 indicates a flexible band, that may be of any suitable material, but

preferably of what is known as "hoop steel." Near one end of the band a stud, or pin, 2 is erected, which may be a separate piece 55 riveted in or it may be "formed up" out of the body of the band. Near the opposite end of the band a plurality of perforations 3, 3 are provided that are adapted to engage over the pin 2, when the band is bent over 60 and the ends superimposed. A clasp 4, comprising a band, or wire, is bent around the band 1 and adapted to slide therealong to engage, and hold the superimposed ends when a perforation is engaged over the pin 65 2 and prevent displacement thereof. The pin 2 will prevent the clasp sliding off the band when the ends thereof are not engaged. A plurality of members 5, 5 are arranged 70 transversely of the band 1, being secured thereto by suitable means such as rivets 6. The clips 5 extend beyond the edges of the band a distance sufficient to allow of their being bent down at an angle thereto, in position to engage the edge of the handle 7 of a 75 basket 8 when the band is in place thereon.

In adjusting the band for service it will be placed under the bottom of a basket, up around the sides and over the handle, drawn taut, and one of the perforations engaged 80 over the pin, the clasp slid over the superimposed end of the band, the clips 5 bent down and engaged under the handle. The clips 5 prevent the band from slipping off the handle and the tensile strength of the 85 band takes care of any load that may be placed in the basket.

Having described my invention so that any one may make and use the same, I claim:—

1. In combination with a basket and the handle thereof, a band encircling said basket and handle, means for connecting the ends of the band and clips extending laterally from the band to engage with said handle to 95 prevent lateral movement of the band thereon.

2. In combination with a basket, a handle attached thereto and extending thereabove, a flexible metallic band adapted to be encircled about said basket and over said handle, said band having a protuberance near one end thereof and being provided with a perforation near the other end

adapted to be engaged over said protuberance, a slide on said band adapted to engage over the superimposed end of the band and retain said perforation in engagement with the protuberance, lugs depending from the edges of that portion of the band that overlies said handle, said lugs being adapted to

bear against each side of the handle and prevent lateral movement of the band thereon.

ADOLPH MARCUS.
